DESIGN FOR A BALL GAME DEVICE

Ralph H. Hayes and Worth L. Smith, Highland Park, Mich.

Application April 13, 1938, Serial No. 76,486

Term of patent 7 years

To all whom it may concern:

Be it known that we, Ralph H. Hayes and Worth L. Smith, citizens of the United States and residents of Highland Park, in the county of Wayne and State of Michigan, have invented a new, original, and ornamental Design for a Ball Game Device, of which the following is a specification, reference being had to the accompanying drawing, forming a part thereof.

We claim:

The ornamental design for a ball game device, substantially as shown.

RALPH H. HAYES.
WORTH L. SMITH.
